UNITED STATES PATENT OFFICE.

HOWARD A. DUDLEY, OF HAGERSTOWN, MARYLAND.

LOOSE-LEAF BINDER.

Application filed November 30, 1921. Serial No. 518,954.

To all whom it may concern:

Be it known that I, HOWARD A. DUDLEY, a citizen of the United States, residing at Hagerstown, in the county of Washington 5 and State of Maryland, have invented new and useful Improvements in Loose-Leaf Binders, of which the following is a specification.

This invention relates to loose-leaf binders 10 and has for one of its objects the construction of a binder in which individual and interchangeable pins are used to retain the core of leaves within the cover of the binder.

Another object of the invention is the 15 provision of a loose-leaf binder in which the pins are inserted from opposite sides of the binder through a plurality of holes, one pin to a hole, each hole being constituted by an aperture through a core of 20 leaves and an aligned aperture through the cover.

Another object of the invention is the provision of tapered pins each projected from opposite sides of the binder through 25 a cylindrical aperture in the core of leaves, the axes of said pins coinciding substantially with the axes of the respective apertures when the core of leaves is intact, but the pins on each side being inclined, when 30 the core of leaves is opened, until their tapered ends engage the upper walls of the cylindrical apertures, in which position the lower surfaces of said tapered pins lie in inclined planes which intersect to form a 35 downwardly facing dihedral angle, permitting a corresponding divergence in the two sections of the cylindrical apertures in the core of leaves which are formed when said core is opened. As the cylindrical apertures of said core are punched perpendicular to the surfaces of the leaves, the greater 40 the divergence of said sections of the cylindrical apertures, the flatter will be the opening of the leaves.

A still further object of the invention is 45 the provision of a cover having hinged flaps embracing between them a core of leaves, there being a plurality of headed pins inserted from opposite sides each through an 50 aperture in one of said flaps and an aligned aperture in said core, and a sheath or guard for each flap having parallel sides embracing said flap and the heads of adjacent pins, the lower side of said sheath or guard 55 being slotted at the proper intervals to

straddle the shanks of the pins beneath the heads thereof, said guard functioning primarily to prevent the heads of the pins from wearing the cover of the binder and secondarily to retain said pins in place. 60

For the attainment of these ends and the accomplishment of other new and useful objects, as will appear, the invention consists in the features of novelty in the construction, combination and arrangement of 65 the several parts generally shown in the accompanying drawings and described in the specification, but more particularly pointed out in the appended claims.

In the drawings:—

Figure 1 represents a transverse sectional elevation of a loose-leaf binder in closed position.

Figure 2 is a similar view of the same binder in wide open position.

Figure 3 is a longitudinal sectional view taken along the line 3—3 of Figure 1.

Figure 4 is a plan view showing the pin-guard.

Figure 5 is a view in perspective showing 80 one half of each of the two oppositely facing pin-guards.

Referring in detail to the several figures the numerals 1 and 2 represent the front and rear portions of the cover of a loose-leaf binder which are foldable as shown in dotted lines at 4, relative to a back portion 5 which may be integral with or attached thereto. Within the back portion 5 is a reinforcing element 6 which is convex on 85 its outer surface 7 to give shape to the back portion 5 and flat on its inner surface 8. The latter surface is covered with any suitable finishing material and forms an abutment for the leaves of the core 15, when the binder is in closed position, as shown in Figure 1. Running longitudinally along the lines of fold 9 and 10, between the front and rear cover portions and the back portion, are the hinged flaps 11 and 12 which 90 are glued or otherwise fastened to the front and rear cover portions by means of the contacting flanges 13 and 14. Between the hinged flaps is embraced the core of leaves which in Figure 2 is shown separated into 95 two sections 16 and 17.

The hinged flaps are each apertured at intervals, as shown by the numeral 18 in Figure 3 and by the small dotted circles 18 in Figure 4. The core section is punched to 100 105 110

form cylindrical openings 20 extending therethrough and in alignment with the apertures 18 in the hinged flaps. The pins 21, which are provided with enlarged heads 22 and cylindrical body portions tapering toward their outer ends are inserted from opposite sides through the apertures 18 in the hinged flaps and the aligned cylindrical openings 20. The heads 22 of the pins and 5 the hinged flaps are held together by means of the guards 23 each of which comprises an elongated strip of sheet metal bent upon itself to form a narrow U-shaped channel member the lower side of which is slotted 10 to register with the shanks of said pins, said guard being adapted to be pushed in place over a hinged flap and the heads of the pins passing therethrough, said guards serving primarily to protect the back of the binder 15 from being worn or marred by the pressure of the projecting heads of the pins, but the guard also acts to an extent as an additional retaining means to prevent displacement of the pins. Said pins are, however, self-re- 20 taining in the sense that when the front and rear portions of the cover are closed they cannot escape and when the core of leaves is opened as shown in Figure 3, said pins co- 25 operate to perform an arcing function which 30 prevents their involuntary extrusion. The function of the pins as leaf-holding and retaining means is therefore not impaired by the omission of the guards and it is a matter of choice in the manufacture or use of the 35 device whether they be employed.

The operation of the binder is clearly indicated in Figures 1 and 3. With the cover opened as shown at 4, Figure 1, the pins 21 may be withdrawn by a rectilinear motion 40 from the cylindrical apertures 20. The withdrawal of two of these pins puts the core of leaves in condition for the removal of any part thereof, as a unit, or any particular leaf. No care is required in the re- 45 insertion of said pins since they are all of the same shape and interchangeable. When the binder is opened as shown in Figure 3, the cylindrical apertures 20 separate into two sections which tend to deviate through 50 an angle causing a relative inclination of the pins on each side permitted by the freedom of motion of the tapered ends of said pins 21 relative to the outer ends of the respective sections of said cylindrical apertures. The 55 limit of this deviation is reached when the tapered ends of said pins abut against the upper walls of said apertures. At this time the lower surfaces of the pins on the respective sides lie in inclined planes which inter- 60 sect, forming a downwardly facing dihedral angle which determines the angular inclination of the two sections of the cylindrical apertures 20, and consequently the flatness of opening of the leaves. As there is prefer- 65 ably some play between the cylindrical aper-

tures 20 and that part of the pins 21 of largest diameter the leaves will open, in practice, a little flatter than would be permitted merely by the acuteness of said dihedral angle. 70

The hinged flaps 11 and 12 will be thrown into relatively divergent positions, due to the weight of the leaves, when the binder is opened, thereby assuming a position of perpendicularity to the axes of the pins when 75 the latter are relatively inclined.

Having described my invention what I claim as new and desire to secure by Letters Patent, is:—

1. A loose-leaf binder comprising front and rear cover portions provided with spaced hinged flaps, each flap being apertured, a core of leaves inserted between said flaps and provided with cylindrical apertures in alignment with the apertures in 85 said flaps, and pins inserted through opposite sides, one through each of said flap apertures and its aligned core aperture.

2. A loose-leaf binder comprising front and rear cover portions provided with spaced hinged flaps, each flap being apertured, a core of leaves inserted between said flaps and provided with cylindrical apertures in alignment with the apertures in said flaps, and tapered pins inserted through 95 opposite sides, one through each of said flap apertures and its aligned core aperture.

3. A loose-leaf binder comprising front and rear cover portions provided with spaced hinged flaps, each flap being apertured, a core of leaves inserted between said flaps and provided with cylindrical apertures in alignment with the apertures in said flaps, pins, headed at one end and having 100 tapered stems inserted from opposite sides 105 one through each of said flap apertures and its aligned core aperture.

4. A loose-leaf binder comprising front and rear cover portions provided with spaced hinged flaps, each flap being apertured, a core of leaves inserted between said flaps and provided with cylindrical apertures in alignment with the apertures in said flaps, pins, headed at one end and having 115 tapered stems inserted from opposite sides one through each of said flap apertures and its aligned core aperture and means for clamping together the flap and the heads of the pins adjacent thereto.

5. A loose-leaf binder comprising front and rear cover portions provided with spaced hinged flaps, each flap being apertured, a core of leaves inserted between said flaps and provided with cylindrical apertures in alignment with the apertures in said flaps, pins, headed at one end and having 120 tapered stems inserted from opposite sides one through each of said flap apertures and its aligned core aperture and a 125 guard having a U-shaped cross section 130

- adapted to embrace each of said hinged flaps and the adjacent pin heads, said guard being slotted on its under side to straddle the stem of each pin beneath the head thereof.
- 5 6. A loose-leaf binder comprising front and rear cover portions provided with spaced hinged flaps, each flap being apertured, a core of leaves inserted between said flaps and provided with cylindrical
- 10 apertures in alignment with the apertures in said flaps and interchangeable tapered pins inserted through opposite sides, one through each of said flap apertures and its aligned core apertures.
- 15 7. A loose-leaf binder comprising front and rear cover portions longitudinally foldable on each side of a back portion, hinged flaps secured to said front and rear cover portions along the lines of fold, said flaps
- 20 lying normally in parallel planes, and being provided with apertures the axes of which are normally in the same plane, a core of leaves inserted between said hinged flaps and provided with apertures in alignment
- 25 with the apertures in said hinged flaps, and pins having enlarged heads and tapered stems inserted from opposite sides, one

through each flap aperture and its aligned core aperture.

8. A loose-leaf binder comprising front and rear cover portions longitudinally foldable on each side of a back portion, hinged flaps secured to said front and rear cover portions along the lines of fold, said flaps lying normally in parallel planes, and being provided with apertures the axes of which are normally in the same plane, a core of leaves inserted between said hinged flaps, 35

40 pins having enlarged heads and tapered stems inserted from opposite sides, one through each flap aperture and its aligned core aperture, and a guard for each flap comprising a folded strip having upper and lower spaced sides embracing and frictionally engaging said hinged flap and the adjacent pin heads, the lower side being slotted to straddle the stem of each pin below the 45

50 head thereof.

In testimony whereof I have hereunto set my hand.

HOWARD A. DUDLEY.
